UNITED STATES PATENT OFFICE.

JOHN L. PALMER AND CHARLES N. WHEELER, OF PEORIA, ILLINOIS.

ELECTRIC FIXTURE.

1,029,557.

Specification of Letters Patent. Patented June 11, 1912.

Application filed May 4, 1911. Serial No. 624,989.

To all whom it may concern:

Be it known that we, JOHN L. PALMER and CHARLES N. WHEELER, citizens of the United States, residing at Peoria, in the 5 county of Peoria and State of Illinois, have invented certain new and useful Improvements in Electric Fixtures; and we do hereby declare that the following is a full, clear, and exact description of the invention, 10 which will enable others skilled in the art to which it appertains to make and use the same.

This invention relates to an improvement in an electric fixture and pertains more particularly to an arm or extension for a fixture body, or wall bracket.

An object of the invention is to provide means for closing the outer end of the hollow arm which carries the electric lamp or 20 bulb, and to combine with said means a fixed or detachable extension or nipple for receiving the lamp socket.

Another object is to so arrange the closure for the end of the arm that both it and the 25 extension or nipple which it carries can be inserted as a unit into the arm, involving but a single operation, the said closure being held in place by friction.

Another object is to furnish one of the 30 walls of the arm with a hole or recess of sufficient size through which to pass the extension or nipple of the closure and through which said extension or nipple can be readily inserted and withdrawn in assembling or disassembling the device.

In the accompanying drawing; Figure 1 is a longitudinal sectional elevation of a hollow arm showing a closure for its end and a lamp holding extension for said closure. Fig. 2 is a similar view showing the closure withdrawn and in position to raise the extension or nipple from the opening in the wall of the arm. Fig. 3 is a similar view except that a side elevation of the closure and nipple is shown, said closure having been raised into the upper part of the arm ready for withdrawal therefrom. Fig. 4 shows the closure and its extension or 45 nipple in perspective. Fig. 5 is a longitudinal section of the arm as shown in the first three figures in which the closure and its extension or nipple are shown as separate parts, and Fig. 6 is a plan of the closure.

It is the desire to provide a very simple 50 arrangement for assembling and disassembling the parts of an arm carrying an elec-

tric lamp, preferably using friction as the method of holding the closure in the end of the arm and in which the closure shall carry an extension or nipple, the latter being 60 either made as an integral part of the closure or as a part separate therefrom, as desired, there being no clamping means employed by which to hold the closure and arm together, the closure and nipple being 65 movable together or as a whole relative to said arm.

A indicates a hollow arm of a fixture or of a wall bracket, neither of which are shown, said arm in the latter instance being 70 secured to the spider of crow-foot (not shown) attached to the wall in the usual manner. The arm serves as a conduit for the conducting wires shown at a in Fig. 3, its outer end being closed by a cap-plate B 75 the inner side of which is provided with an integral extension C which, preferably, is made in some such form as shown in Fig. 4 whereby its parts will engage the inner wall surfaces of the arm and preferably 80 slightly tapered so as to have a snug driving fit into said arm, said cap-plate or portion B acting as a stop by engaging the end of the arm and also as a grasping piece. However, it is not our intention to confine 85 ourselves necessarily to the exact form of this extension since if desired the side portions C', Fig. 4, may be eliminated or such other changes may be made as will lie within the meaning of the invention, it being 90 desired only that sufficient frictional surface be provided to hold the closure or cap-plate firmly in position and such changes as may be desired may be made in the construction of said cap-plate as will fall within the invention. 95

The closure has an inwardly extending tongue D also tapered toward its extremity, as indicated in Fig. 6, so that it will have a long driving fit into the arm and this said 100 tongue preferably has its position in the lower part of the arm, or at least that part which is to carry the lamp, and carries an exteriorly threaded extension or nipple E whose threaded part is located exteriorly of 105 the arm A, as indicated at F, said nipple being provided with a bore G.

As clearly illustrated, the arm A is provided in its lower wall near its end with a hole H somewhat larger in diameter than 110 the nipple E through which said nipple can be inserted and within which it is sus-

pended. This nipple, as shown, and as stated previously, may be a part of the closure B, or its tongue D, or it may be threaded into the latter as indicated at J in Fig. 5 5 in which figure the said member is represented by K, the hole in the arm being indicated by H'. When driven into place within the arm the closure is firmly held by friction through the extension C, its side 10 portions C', and said tongue D, and it will be noted that when in its normal position the nipple lies freely within the hole H and does not touch the arm.

The lamp socket indicated at L is spaced 15 from the arm and although the position of the latter in this respect is not important it does not of necessity help to hold the tongue D and the arm together.

In assembling the device the several operations represented in Figs. 3, 2 and 1 respectively are followed. In said Fig. 3 it is noted that the tongue D has been inserted in the end of the arm with the nipple opposite the hole H, and in Fig. 2 it has been 20 carried into the lower part of the arm to place said nipple in said hole H, while in Fig. 1 the extension C is inserted into the end of the arm and driven up to its normal position. The hole is large enough to permit the nipple to enter it while the top part 25 of the extension C is outside of the arm as shown and so that the extension may afterward be pushed to its place thus giving the nipple sufficient room to shift laterally in 30 both the assembling and disassembling operations. In disassembling, of course, the same movements are followed but in the reverse order. It is clear that if we resort to 35 extending the hole H into a slot having an outer open end, the tongue and its nipple 40 may be slipped directly into position.

Our device is exceedingly simple in construction and we have a minimum of parts which admits of a device of this kind being 45 made at a very low cost and the time necessary to assemble or disassemble is practically nothing. But where a device is made up of parts so arranged that all are clamped on the arm together much time is required 50 to assemble them and complications of various kinds arise and the time necessary for assembling, as well as the cost, is greater in comparison.

As intimated, it is not our wish to confine 55 ourselves to the exact structures herein described and shown since such changes may be made as will fairly lie within the scope of the invention and its claims.

Having described the invention we 60 claim:

1. As a new article of manufacture, a member having an open end and adapted for carrying an electric lamp, and having an opening in one of its walls, a member to 65 close the said open end and having a part

to engage the first said member by friction, said part having an extension or nipple adapted to pass freely through and suspended in said opening and adapted to receive a lamp.

70

2. As a new article of manufacture an arm having an open end and provided with an opening in one of its walls, a member to close said open end and having a part to frictionally engage one of the walls of the 75 arm and provided interiorly of the arm with an extension or nipple adapted to enter said opening of the wall and suspended in and below the same and threaded on its extremity exteriorly of the arm.

80

3. As a new article of manufacture, an arm having an open end and provided with an opening in one of its walls, a member to close said open end and having a part to frictionally engage the inner wall of the 85 arm and provided interiorly of said arm with an extension or nipple adapted to freely pass into said opening of the wall and suspended in and below the same and adapted to receive a lamp socket.

90

4. As a new article of manufacture, an arm having an open end and provided with an opening in one of its walls, a member to close said open end and having a part to frictionally engage said arm and also having an extension interiorly of the arm provided with a second extension or nipple to enter the opening of the wall and depending therein, said opening being of larger diameter than the greatest diameter of the 100 nipple, said nipple having provision to hold a lamp socket.

95

5. As a new article of manufacture, an arm having an open end and provided with an opening in its side, a member to close 105 said open end and having a part to detachably engage the arm by friction and provided with a depending extension or nipple to receive a lamp socket.

105

6. As a new article of manufacture, an 110 arm having an open end and a hole in its side, a member to close said open end and having a part to detachably engage the arm by friction and provided with an integral extension or nipple adapted to pass into the 115 open end of the arm and adapted to enter the hole in a direction perpendicular to the direction of its passage into said arm.

110

7. As a new article of manufacture, an arm having an open end, a member to close 120 said open end and having a part to detachably engage the arm by friction and carrying an extension or nipple adapted to receive and carry a lamp socket.

120

8. As a new article of manufacture, a 125 member for carrying an electric lamp having an opening in one of its side walls and an opening at its end, and a member adapted to enter the opening in said end and provided with an extension or nipple smaller in 130

diameter than the opening in the side wall and adapted to pass freely through the same, and threaded at its end outside the wall to receive a lamp socket.

- 5 9. As a new article of manufacture, a tubular member having an open end, and provided with an opening in its wall, a member adapted to detachably engage the first by friction and carrying an extension 10 adapted to freely pass into said opening and adapted to hold a lamp socket, and having a part exteriorly of the first member larger in diameter than the bore of that member.
- 15 10. As a new article of manufacture, an arm having an open end and an opening in its side, a member lying in and snugly fitting said open end and having an integral extension or nipple for insertion into and to 20 extend through said opening and adapted to receive a lamp socket.
11. As a new article of manufacture, an arm having an open end and an opening in its side wall, a member to slidably engage

the inner walls of the arm, and having a 25 part extending inward from the slideable portion, said part having an extension or nipple projecting therefrom substantially at right angles, and adapted to extend through the opening of the arm to receive a lamp 30 socket.

12. As a new article of manufacture, an electric fixture arm having an open end, a member overlying said open end comprising a flat body having an integral extension 35 projecting from one of its sides substantially at right angles to its plane and narrower than the side from which it projects, and a nipple projecting from one side of the said extension disposed substantially 40 parallel to the plane of said body.

In testimony whereof we affix our signatures, in presence of two witnesses.

JOHN L. PALMER.

CHARLES N. WHEELER.
